FURNITURE PEDESTAL

Ronald H. Beckman, New York, N.Y., assignor to Herman Miller, Inc., Zeeland, Mich., a corporation of Michigan

Filed Nov. 27, 1964, Ser. No. 82,824

Term of patent 14 years

(Cl. D33—14)

FIG. 1 is a perspective view of the furniture pedestal of my novel design;

FIG. 2 is an end elevational view of the pedestal taken from the right end of the pedestal as shown in FIG. 1;

FIG. 3 is a sectional view of the top portion of the pedestal, taken on plane III—III of FIG. 2;

FIG. 4 is a sectional view of the top portion of the pedestal taken on plane IV—IV of FIG. 2; and

FIG. 5 is a sectional view of the support column of the pedestal taken on plane V—V of FIG. 2.

I claim:

The ornamental design for a furniture pedestal, substantially as shown.
